Assistant Examiner — Russell Carnell Smith, Jr.

CLAIM

The ornamental design for a TV mount, as shown and described.

DESCRIPTION

FIG. 1 is a front perspective view of a TV mount showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a perspective view of the use state of a TV mount. The broken lines illustrate portions of the TV mount that form no part of the claimed design.

1 Claim, 9 Drawing Sheets
